CONVEYER

Harry D. Lathrop, Chicago, Ill., assignor to The Lathrop-Paulson Co., a corporation of Illinois

Application August 22, 1936, Serial No. 97,445

12 Claims. (Cl. 198—137)

This invention relates to conveyor apparatus and more particularly to apparatus adapted to convey bottles and other articles of varying dimensions.

5 An object of the invention is to provide conveyor apparatus of simple and sturdy construction which may conveniently be adjusted to accommodate bottles and other articles of various widths and sizes. A specific object is to provide 10 improved means for adjusting the guide rails to allow articles of different sizes to pass between them and improved means for holding the rails in a desired position.

Other objects and advantages will appear as 15 the specification proceeds.

The invention is illustrated in a preferred embodiment by the accompanying drawings, in which—

Figure 1 is a vertical sectional view showing 20 the rails in position to accommodate a larger bottle, the section being taken as indicated at lines 1—1 of Fig. 3; Fig. 2, a view similar to Fig. 1 but showing the rails in position to accommodate a smaller bottle; Fig. 3, a side view in elevation of the device; and Fig. 4, a vertical sectional view showing the frame structure, the section being taken as indicated at lines 4—4 of Fig. 3.

In the illustration given, A represents a frame; 30 B the guide rails and their supporting arms; and C, a means for moving the rail arms about their pivots.

The frame A may be of any suitable construction. As illustrated it comprises the side members 10 and 11 between which are the upper and lower chain supports 12 and 13. Chain guides 14 may be provided for guiding the movement of the chain. At the upper ends of members 10 and 11 are apertured bearings 15 and 40 16 in which rail arms may be mounted. Member 11 contains apertured bearing 16 which is adapted to receive the rocker shaft. Secured to member 11 is the locking plate 17 containing apertures 18 for receiving the locking pin.

45 A conveyor chain 19 may pass over the top chain support 12 and return over the lower chain support 13. The chain may be of any suitable type and driven by any suitable means, but it is preferred to employ a continuous chain composed of pivotally connected units. A cross-section of one link of such a chain is shown in Figs. 1 and 2 of the drawings.

The guide rails 20 and 21 are tubular members located above and at each side of the conveyor 55 chain 19. They are supported by the rail arms

22 and 23. Rail arms 22 and 23, preferably identical, are provided at their top ends with jaws 24 which may be tightened about rails 20 and 21 by bolts 25. The rail arms 22 and 23 are pivotally mounted on frame A at bearings 15 and 16 by pins 26. Arms 22 and 23 have lower extensions 27 which are provided with pins or shafts 28 and 29. It is understood that there may be several arms such as rail arm 22 on one side of the chain and the extension 27 on all of these arms may be connected by shaft 28, and similarly shaft 29 may engage extensions on all arms 23.

The means C for rotating arms 20 about their pivoted points includes a rocker shaft 30, the upper end of which contains a slot 31 which engages shaft 29. The lower end of rocker arm 30 is pivotally connected with link 32 which is in turn pivotally connected to shaft 28. A rocker shaft 33 journaled in bearing 16 of frame A is 20 keyed to the center portion of rocker arm 30. The link 32 contains a slot 34 through which shaft 33 may extend and which allows link 32 to move laterally as arm 30 is rotated.

Also secured to rocker shaft 33 is the crank 25 arm 35 which is equipped with a spring-pressed lever 36. Lever 36 is equipped at its end with a pin 37 which is urged by the spring through aperture 38 in lever 36 and through one of apertures 18 in locking plate 17.

In the operation of the device when it is desired to convey relatively small bottles or articles, the operator grasps crank 35 and lever 36, compressing the spring and moving pin 37 out of engagement with plate 17. By pulling crank 35 downwardly rocker shaft 33 is caused to rotate which in return causes rotation of rocker arm 30. Shaft 29 slides along slot 31 and rail arms 23 are moved about their pivots causing rail 21 to move inwardly toward the center of chain 19. At the same time link 32 moves laterally, slot 34 moving over rocker shaft 33 and causes rail arms 20 to move about their pivots which brings rails 20 inwardly toward the center of the chain 19.

Adjustment for bottles or articles of larger 45 size may be had by moving crank arm 35 in upward direction in which case movements of the various parts are in direction opposite that set out above.

The rails may be locked in one of several positions as desired by allowing pin 37 to engage one of the several apertures 18 in plate 17.

It will be observed that when large bottles are being conveyed, the rails are moved upwardly and outwardly, while when smaller bottles are 55

conveyed, the rails are moved downwardly and inwardly, thereby maintaining the rails in substantially the same relative position with respect to the height of the bottles.

5 While in the foregoing description I have described a specific construction, it will be understood that great variation can be made from the details shown without departing from the spirit of my invention. The detailed description has 10 been given for clearness of understanding only, and no unnecessary limitations should be understood therefrom, but the appended claims should be construed as broadly as permissible, in view of the prior art.

15 I claim:

1. In a device of the character set forth: a frame; a conveyer chain supported in said frame; guide rails spaced apart on each side of the center of said chain, said rails being supported by 20 rail arms pivotally supported at fixed points in said frame; and singly actuated means for moving said rail arms about their pivots to vary the vertical position of said rails and the spacing between them.

25 2. In a device of the character set forth: a frame; a conveyer chain supported in said frame; guide rails above and at the sides of said chain; pivotally supported rail arms having their top ends attached to said rails, said rail arms being 30 equipped with extensions below their points of pivot; and means engaging the lower ends of said extensions for moving said rail arms about their pivots whereby said rails are moved toward or away from each other.

35 3. A device of the character set forth, comprising: a frame; a conveyer chain supported in said frame; guide rails above and at the sides of said chain; rail arms pivotally mounted in said frame, said arms being movable about a substantially 40 horizontal axis and attached to said rails; a rocker member pivotally mounted on said frame; means for pivotally connecting said member at its one end to a rail arm on the other side of said chain; and means for moving said member about 45 its pivot to simultaneously move said rails toward or away from the center of said chain.

4. A device of the character set forth, comprising: a frame; a conveyer chain supported in said frame; spaced guide rails above and on each side 50 of said chain, said rails being supported by rail arms pivotally supported on said frame on fixed substantially horizontal axes; means for moving said arms simultaneously about their pivots to vary the spacing between said rails, said means including a pivoted rocker member having its 55 ends movably connected with rail arms on different sides of said chain.

5. A device of the character set forth, comprising: a frame; a conveyer chain supported in said 60 frame; spaced guide rails above and on each side of said chain, said rails being supported by rail arms pivoted about fixed points in said frame; means for moving said arms simultaneously about their pivots to vary the spacing between said rails, said means including a rocker shaft 65 held in said frame, a rocker member having its one end movably connected with at least one rail arm on one side of said chain, and a link connecting the other end of said member with at 70 least one rail arm on the other side of said chain, said link containing a slot which is engaged by said shaft.

6. A device of the character set forth, comprising: spaced guide rails above and on each side 75 of each chain, said rails being supported by rail

arms pivoted about fixed horizontal axes in said frame; means for moving said arms simultaneously about their pivots to vary the spacing between said rails; and means for releasably holding said arms in a predetermined angular position about their pivots. 5

7. A device of the character set forth, comprising: a frame; a conveyer chain supported in said frame; spaced guide rails above and on each side of said chain, said rails being supported by rail 10 arms pivotable about fixed points in said frame; means for moving said arms simultaneously about their pivots to vary the spacing between said rails; said means including a rocker shaft held in said frame, a rocker member secured to 15 said shaft, said member having its one end movably connected with a rail arm on one side of said chain and its other end movably connected to a rail arm on the other side of said chain; and a crank arm also secured to said shaft, said crank 20 arm being equipped with releasably locking means for engaging said frame.

8. In combination with conveyer apparatus including: a frame and equipped with a conveyer chain and guide rails; rail arms pivotally mounted about substantially horizontal axes in said frame and supporting said guide rails; a rocker shaft supported in said frame and connecting means between said shaft and said arms for securing an arm on one side of said chain in position for rotation in the same direction as said shaft and for securing an arm on the other side of said shaft in position for rotation in a direction opposite that of said shaft. 25

30 9. A device of the character set forth, comprising: a frame; a conveyer chain supported in said frame; spaced guide rails above and on each side of said chain, said rails being supported by rail arms pivotable about fixed points in said frame; means for moving said arms simultaneously about 35 their pivots to vary the spacing between said rails, said means including a rocker shaft held in said frame, a rocker member having its one end movably directly connected with at least one rail arm on one side of said chain, and a link connecting the other end of said member with at least one rail 40 arm on the other side of said chain. 45

10. A device of the character set forth, comprising: a frame; a conveyer chain supported in said frame; spaced guide rails above and on each side 50 of said chain, said rails being supported by rail arms pivotable about fixed points in said frame; means for moving said arms simultaneously about their pivots to vary the spacing between said rails; said means including a rocker shaft held in said frame, a rocker member secured to said shaft, said member having its one end movably directly connected with a rail arm on one side of said chain and its other end movably connected to a rail arm on the other side of said chain; and means for effecting a turning movement of said shaft to vary 55 the spacing between said rails. 60

11. A device of the character set forth, comprising: a frame; a conveyer chain supported in said frame; spaced guide rails above and on each side of said chain, said rails being supported by rail arms pivotably supported at fixed points in said frame to rock on substantially horizontal axes; means for moving said arms simultaneously about 70 their pivots to vary the spacing between said rails, said means including a rocker shaft held in said frame, a rocker member having its one end movably connected with at least one rail arm on one side of said chain, and a link connecting the other 75

end of said member with at least one rail arm on the other side of said chain.

12. A device of the character set forth, comprising: a frame; a conveyer chain supported in said frame; spaced guide rails above and on each side of said chain, said rails being supported by rail arms pivotally supported at fixed points in said frame to rock on substantially horizontal axes; means for moving said arms simultaneously about their pivots to vary the spacing between said

rails, said means including a rocker shaft held in said frame, a rocker member secured to said shaft, said member having its one end movably connected with a rail arm on one side of said chain and at its other end movably connected to a rail arm on the other side of said chain; and means for effecting a turning movement of said shaft to vary the spacing between said rails. 5
